CLAIM

(22) Filed: **May 11, 2005**

The ornamental design for a non-electric household food slicer, as shown and described.

(30) **Foreign Application Priority Data**

DESCRIPTION

Nov. 11, 2004 (EM) 000252960

FIG. 1 is a top, front and side perspective view of a non-electric household food slicer, showing my new design; FIG. 2 is a side elevational view thereof;

(51) **LOC (8) Cl.** **07-04**

FIG. 3 is a side elevational view thereof from the side opposite that shown in FIG. 2;

(52) **U.S. Cl.** **D7/693; D7/381**

FIG. 4 is a top plan view thereof;

(58) **Field of Classification Search** D7/693,

FIG. 5 is an end elevational view thereof from the right of FIG. 2;

D7/376-383; 134/6; 241/95, 273.1-273.5;

FIG. 6 is an end elevational view from the left of FIG. 2;

83/856, 858, 859, 663, 451, 452, 733, 478,

FIG. 7 is a bottom plan view thereof; and,

83/91, 102, 104, 167, 168, 701

FIGS. 8-14 are views similar to FIG. 1-7, respectively, but showing the parts in a different position.

See application file for complete search history.
